UNITED STATES PATENT OFFICE

CARROLL R. ALDEN, OF DETROIT, MICHIGAN, ASSIGNOR TO EX-CELL-O AIRCRAFT AND TOOL CORPORATION, OF DETROIT, MICHIGAN, A CORPORATION OF MICHIGAN

FUEL PUMP

Application filed January 3, 1928. Serial No. 244,077.

This invention relates generally to improvements in fuel pumps for forming the charges for internal combustion engines, and more particularly to the construction of a control valve in a pump for an engine of the Diesel type.

In the operation of fuel pumps of the above type, the injection of fuel oil under pressure into the engine cylinder takes place during the expulsion stroke of the pump piston and is terminated or cut off by suddenly decreasing the pressure within the pump cylinder. This is usually effected by mechanically opening a valve which allows the oil under high pressure in the pump cylinder to be by-passed into an auxiliary chamber which is usually filled with fuel oil. It has been found in practice that this sudden release of pressure and the initial rush of oil at high velocity into a body of oil in a static state causes considerable noise or "knocking." In addition the initial flow of oil through the by-pass valve at high velocity causes such impingement of the oil particles as to result in the formation of bubbles of oil vapor. This condition is particularly disadvantageous where the same valve is used as an intake valve, there being in such construction a tendency to draw the compressible vapor bubbles back into the pump cylinder in the next intake stroke of the pump piston.

The primary object of the present invention is to provide a Diesel engine fuel pump having a new and improved valve structure for efficiently controlling the point of cut-off of fuel injection by releasing instantaneously the pressure in the pump cylinder without the usual knocking and by preventing any back flow into the pump cylinder of oil carrying vapor or other compressible gases.

Another object is to provide a novel valve of the above character which also functions as an intake valve during the suction stroke of the pump piston and as a means for preventing back flow of the fuel oil to the supply line during injection of the oil into the engine cylinder.

In carrying out these objects, I provide separate outlet passageways from the fuel pump cylinder, one preferably leading to the

constantly drained chamber into which the oil can flow freely and the other leading to the oil supply line, two valves being provided to control said passageways and operable successively at the point of cut-off to allow a small volume of the oil to be by-passed from the pump cylinder into said chamber and the remainder to flow back into said fuel supply line. The arrangement of the valves is such that the oil initially by-passed from the cylinder is positively entrapped in said chamber and thereby prevented from being drawn back into the cylinder during the succeeding suction stroke of the pump piston.

Other objects and advantages of the invention will become apparent from the following detailed description taken in connection with the accompanying drawings, in which,

Figure 1 is a vertical sectional view through a Diesel engine fuel pump equipped with a control valve embodying the features of the present invention.

Fig. 2 is a fragmentary view showing the valve structure in vertical section.

Figs. 3 and 4 are enlarged views of the valve under different operating conditions.

Fig. 5 is a section taken along line 5-5 of Fig. 4.

While the invention is susceptible of various modifications and alternative constructions, I have shown and will herein describe in detail the preferred embodiment but it is to be understood that I do not thereby intend to limit the invention to the specific form disclosed but intend to cover all modifications and alternative constructions falling within the spirit and scope of the invention as expressed in the appended claims.

In the drawings, the fuel pump chosen for the purpose of illustrating my improved valve structure is of the reciprocatory type and includes a casing 6 adapted to be secured to the Diesel engine adjacent the cylinder 9 thereof to be supplied with fuel charges by the pump. A countershaft 7 driven in properly timed relation to the crank shaft of the engine is rotatably supported by the casing and carries a cam 8 which acts on a roller 9.

to periodically raise a vertical tappet member 10.

Seated in the upper end of the tappet is a piston 11 which reciprocates in a cylinder 12 provided by a block 13 threading into a solid metal head 14 on the casing 6. A strong compression spring 15 acting against the block serves to move the piston downwardly on its suction stroke as permitted by the rotation 10 of the cam 8 after its high point 16 has passed the roller 9.

The pump cylinder communicates through a narrow duct 17 in the head 14 with a pressure chamber 18 which is adapted for communication with the cylinder of the Diesel engine through the central bore in a plug 19 and a tubular conduit 20. The flow of oil through the bore is controlled by an automatically operable valve 21 preferably of the pump type having a spring pressed member mounted for reciprocation toward and from a seat in the plug 19.

Fuel oil is admitted to the pressure chamber during the suction or downward stroke 25 of the piston 11 and is expelled therefrom during the upward stroke, being thereby injected under pressure into the engine cylinder through the valve 21 or by-passed out of the chamber through auxiliary passageways controlled by the valve structure generally designated by the numeral 22.

In the present instance this valve structure comprises two valves formed by two coaxially arranged and relatively movable members 23 and 24 disposed in a central bore 25 of a block 26 which is secured by a screw 27 in a counterbored recess in the head 14. The outer member 23 together with its stationary seat constitutes the main by-pass valve 28 for controlling the flow of oil out of the chamber 18 after termination of the oil injection and in the present instance also operates to control the admission of oil into the chamber 18 as well as to prevent the flow 45 therefrom during injection. At its lower end the member 23 has a stem of circular cross section (Fig. 5) mounted for reciprocation in the bore 25. A head 29 is formed at the upper end of the member with downwardly converging sides which are adapted to be seated on the upper peripheral edge of the bore 25 which is flared outwardly slightly at its upper end. Thus an annular passage 33 is formed around the member 23 55 within the bore 25, communication between this passage and an annular chamber 31 being established through ports 32 formed in the block 26 so as to be open for all positions of the member 23. The chamber 31 is continuously supplied from a duct 33 with fuel oil preferably under a primary pressure somewhat above that of the atmosphere. It will be seen that when the valve member 23 is raised from its seat (Fig. 5) a relatively large 60 passageway is provided for the flow of oil in

either direction between the supply duct 33 and the chamber 18, the direction of flow being dependent upon the relative pressures at the two points. The passage 30, the ports 32 and the chamber 31 are intended to be completely filled with oil at all times during the operation of the pump.

Preferably the valve member 24 is formed with a portion fluted as shown in Fig. 5 and mounted for reciprocation in a central bore 34 which extends axially through the member 23. At its lower end the member 24 has converging surfaces 35 adapted to be seated on the upper peripheral edge of an opening defined by shoulders on the member 23 at the lower end of the bore 34. A stem 35^a projects through the opening to a point slightly below the lower end of the member 23. Projecting upwardly through the bore 34 is a shank 36 of small cross section which carries at its upper end a plate 36^a in which a compression spring 37 is seated. This spring acts between the plate 36^a and the lower end of the plug 19 thereby tending to hold the valve member 24 seated which in turn operates to seat the member 23. A compression spring 38 encircling the shank 36 and acting between the upper end of the fluted portion of the member 24 and a retaining ring 39 tends to move the member 23 upwardly relative to the member 24, thereby raising the movable seat of the latter. Thus, it will be observed that the member 24 together with its movable seat constitutes a valve 40 which hereinafter will be termed the auxiliary by-pass valve and which is adapted to control the flow of oil from the chamber 18 past the fluted portion of the member 24 into a recess 41 below the bore 25. This recess is continuously drained by a duct 42 communicating therewith but separate from the fuel oil supply duct 33.

In the present instance, the two valve members 23 and 24 are arranged to be operated to determine the points at which injection of the fuel oil into the engine cylinder will commence and cease. This is accomplished through the medium of an adjustable tappet rod 43 mounted for vertical reciprocation in timed relation to the movements of the engine piston. The lower end of the rod is supported by a plunger 44 and the upper end fits into a member 45 which is guided in its reciprocation by the lower end of a block 46 herein threaded into the casing head 14. A spring 47 encircling the block 46 tends to lower the rod 43.

Seated on the member 45 and extending through a central bore in the block 46 is a plunger 48 having at its extreme upper end a projection 49 adapted to strike the stem 35^a of the valve member 24 as the tappet rod 43 is raised. A cap 50 adjustably threaded on the end of the plunger 48 is

adapted to strike the lower end of the member 23 during the upward movement of the tappet rod 43 but subsequent to the time when the member 24 is engaged by the projection 5 49. With this arrangement, it will be observed that the two valve members 23 and 24 are actuated successively as the tappet rod 43 is raised.

In the pump herein illustrated, two independent mechanical means are provided for controlling the movements of the tappet rod 43 to determine, in one case, the point during the expulsion stroke of the piston 11 at which fuel oil will be injected into the engine cylinder and, in the other case, the point of cut-off, that is, the point at which injection ceases.

Herein the point of injection is controlled by holding the tappet rod 43 raised during the initial part of the upward stroke of the 20 piston 11, part of the charge in the pump cylinder being by-passed therefrom and then allowing the rod 43 to fall and close the valve 28. Referring to Fig. 1, the means herein employed for this purpose comprises an arm 51 25 swingably mounted on a shaft 52 and carrying a roller 53 for following the surface of a cam 54 on the countershaft 7 and a second roller 55 engaging the lower end of the plunger 44. Thus, for any given setting of the axis 30 of the shaft 52, the cam 54 will operate the arm 51 so as to hold the valve 28 open during the major portion of the suction stroke of the piston 11 and for a predetermined interval after the pump piston has started on its 35 expulsion stroke, after which the valve 28 will be allowed to close. With this valve closed further displacement of the piston will force the oil in the pump cylinder through the valve 21 into the engine cylinder.

40 The point of cut-off, in the present embodiment, takes place in timed relation to the movement of the piston 11 and is effected by raising the tappet rod 43 which operates the valves 28 and 40 in a manner to be presently 45 described in detail. The tappet rod 43 is raised through the medium of a lever 56 pivotally mounted at one end on a shaft 57 and having its other end connected to the tappet rod 10. This lever carries an adjustable stop 58 which, after the plunger has progressed a 50 predetermined distance on its expulsion stroke, strikes a collar 59 on the tappet rod 43 thereby raising the same.

55 The operation of the valve structure during one charge forming cycle of operation of the pump will now be described. Assuming that the pump piston is completing its suction or downward stroke, the valve 21 would be closed, the tappet 43 would be held raised as shown in Fig. 4 by the high portion of the cam 54. Thus the projection 49 would hold the valve member 24 raised against the action 60 of the spring 37, the spring 38 then functioning to hold the member 23 in raised position with the valve 40 closed and the valve 28 open.

Under these conditions, oil is being drawn through the valve 28 into the chamber 18, the duct 17 and the pump cylinder.

As soon as the piston 11 starts on its upward or expulsion stroke, that is, when the point 60 on the cam 8 contacts the roller 9, the direction of flow of oil is reversed, oil in the chamber 18 being by-passed back through the open valve 28 into the supply duct 33. Since the valve 40 is held closed at this time by the action of the spring 38 and the pressure of the oil in the chamber 18 which exceeds that in the recess 41, no oil will be by-passed into the recess 41. Later in the expulsion stroke when the cam 54 has advanced sufficiently to allow the valve 28 to be closed by lowering of the tappet rod 43 thereby preventing further by-passing, the oil in the pump cylinder is placed under high pressure. Then the valve 21 opens automatically and a portion of the oil is forced into the engine. This condition of the pump is illustrated in Figs. 1 and 2. Injection of the oil at high pressure continues until the tappet rod 10 has been raised sufficiently to carry the stop 58 against the collar 59. This raises the tappet rod 43 carrying the projection 49 against the stem 35^a, thereby raising the member 24 from its seat, as shown in Fig. 3. At this instant the pressure of the oil in the chamber 18 acting on the upper end of the valve member 23 exceeds the force exerted upwardly on the member by the spring 38 and the primary pressure in the passage 30; consequently the valve 28 is held closed.

With the valve 40 thus opened, the oil under high pressure in the chamber may flow along the fluted portion of the member 24 and around the stem 35^a into the recess 41. Since the recess is preferably constantly drained and at atmospheric pressure, practically no resistance is offered to the flow of oil so that the initial rush through the valve will be at high velocity, the pressure within the chamber 18 being dissipated substantially instantaneously. Owing to the small size of the auxiliary valve 40 only a small volume of oil will be by-passed therethrough and any vapor bubbles formed by the high velocity flow will be entrapped in the recess 41.

As soon as the pressure within the chamber 18 has been reduced to a point where it is overcome by the force of the spring 38 and the pressure within the passage 30, the valve member 23 is allowed to rise relative to the member 24. As shown in Fig. 4, this closes the valve 40 and opens the valve 28 so that the fuel displaced by further rise of the pump piston 11 is by-passed through the valve 28 against the primary fuel pressure back into the supply duct 33. This mode of operation would be likely to take place when the engine is running at a rather slow speed. The valve member 23 may also be raised to open the valve 28 by the progressive upward movement of the tappet rod 43, such action taking

place when the upper end of the cap 50 strikes the member 23. This would probably be the case when the engine is running at higher speeds when the pressure reduction within the chamber 18 does not take place rapidly enough to allow for operation of the member 23, as above described, before the cap 50 engages the member. Opening of the valve 28 which provides a substantially greater passageway than the auxiliary valve 40 instantaneously reduces the pressure within the chamber 18 to such a point as to allow the spring 38 to raise the member 23 away from the cap 50 (Fig. 4). By the reduction of pressure above described, further injection of oil into the engine cylinder is prevented and for the remainder of the expulsion stroke of the pump piston oil is by-passed back into the supply duct 33 against the primary pressure therein.

It will be seen that at the point of cut-off in the pump cycle, the valves 40 and 28 are opened in quick succession and that substantially instantaneously thereafter the valve 40 is closed. Thus only that portion of the by-passed oil which is apt to have vapor bubbles formed therein due to the initial outrush at high velocity, is allowed to pass into the drain recess 41 and this is a comparatively small part of the oil to be by-passed since the valve 40 is of small capacity and is held open only momentarily. Practically no resistance is offered to this flow of oil and therefore the pressure in the pump cylinder is reduced substantially instantaneously without the occurrence of knocking which usually takes place in pumps wherein cut-off is effected by initially by-passing the oil into a chamber already filled with oil in the static state. Since only a small volume of the oil flows through the valve 40, the primary pressure which is usually maintained in the supply chamber 30 is not wasted.

When the high point 16 of the cam 8 passes the roller 9 so that the pump piston starts on its downward or suction stroke, the direction of flow of the oil through the main valve 28 reverses flowing from the supply duct to the chamber 18. At this time the valve members 23 and 24 are positioned as shown in Fig. 4 by the combined action of the lever 56 and the cam 54 acting to hold the tappet rod 43 in raised position. Since the valve 40 is held closed by the spring 38 and by the excessive primary pressure under which the oil supply is placed, none of the turbulent oil previously by-passed into the recess 41 can be drawn back through the valve 40 into the chamber 18. In other words, the auxiliary by-pass 40 allows for the flow of fluid in one direction only since any pressure difference between the chamber 18 and the recess 41 which would tend to permit a flow of the by-passed oil upwardly through the valve 40 would allow the spring 38 to raise the valve

member 23 thus seating the member 24. Thus, all the oil which is apt to contain vapor bubbles is positively entrapped in the recess 41 and is kept separate from the remainder of the oil by-passed subsequent to the point of cut-off.

It will be apparent that the valve construction above described is adapted to accomplish its intended functions in an efficient and reliable manner and with the speed which is required in the operation of a fuel pump for the Diesel type of engine. All of the parts of the valve are simple in construction and adapted to be compactly assembled and conveniently operated from the engine to which the pump is applied.

I claim as my invention:

1. In a pump for supplying liquid fuel to the cylinder of an internal combustion engine, the combination of means providing a fuel receiving chamber adapted for communication with said cylinder, a piston operated from said engine and adapted on one of its strokes to compress the fuel in said chamber, a second chamber normally filled with liquid fuel, a third chamber normally drained, a main by-pass valve member having a stationary seat and providing a valve which when opened establishes communication between said first and second chambers, an auxiliary valve member extending axially of said first mentioned member and cooperating with a seat thereon to provide a valve controlling the flow of fuel from said first mentioned chamber to said third chamber, spring means acting on said auxiliary member and tending to hold both of said members seated, spring means tending to move said main member relative to said auxiliary member whereby to maintain said auxiliary valve closed, and means operable during the expulsion stroke of said piston to terminate the injection of fuel into said cylinder including a mechanism driven from the engine and operating to open said auxiliary valve whereby to relieve pressure in said first mentioned chamber.

2. In a pump for supplying liquid fuel to the cylinder of an internal combustion engine, the combination of means providing a fuel receiving chamber adapted for communication with said cylinder, a piston operated from said engine and adapted on one of its strokes to compress the fuel in said chamber, a source of fuel supply, a second chamber normally drained and free from liquid fuel, two coaxially arranged and relatively movable members cooperating to provide two valves, one permitting the flow of fuel from said first mentioned chamber into said second chamber only, said other valve permitting the flow of fluid in either direction between said first mentioned chamber and said source of supply, and means actuated by said engine and operable at a predetermined point in the expul-

sion stroke of said piston to open said valves successively.

3. In a pump for supplying fuel under pressure to the cylinder of an internal combustion engine, the combination of means providing a chamber for receiving liquid fuel and adapted for communication with said cylinder, a piston reciprocated by said engine and adapted on its expulsion stroke to compress the fuel in said chamber, a source of fuel supply, a second chamber, and means for terminating the injection of fuel into said cylinder by by-passing the fuel from the first mentioned chamber including a main valve controlling the flow of fuel between said first mentioned chamber and said source of supply, an auxiliary valve controlling the flow of fuel from said first mentioned chamber to said second chamber, means operable at a predetermined point in the expulsion stroke of said piston to open said auxiliary valve and said main valve successively, and means operable after a predetermined reduction in pressure in said first mentioned chamber to close said auxiliary valve.

4. In a pump for supplying fuel under pressure to the cylinder of an internal combustion engine, the combination of means providing a chamber for receiving liquid fuel and adapted for communication with said cylinder, a piston reciprocated by said engine and adapted on its expulsion stroke to compress the fuel in said chamber, a source of fuel supply, a second chamber, and means for terminating the injection of fuel into said cylinder by by-passing the fuel from the first mentioned chamber including a main valve controlling the flow of fuel between said first mentioned chamber and said source of supply, an auxiliary valve controlling the flow of fuel from said first mentioned chamber to said second chamber, means operable at a predetermined point in the expulsion stroke of said piston to open said auxiliary valve, and means operable after the pressure in said first mentioned chamber has been reduced to a predetermined point to open said main valve and close said auxiliary valve.

5. In a pump for supplying fuel under pressure to the cylinder of an internal combustion engine, the combination of means providing a chamber for receiving liquid fuel and adapted for communication with said cylinder, a piston reciprocated by said engine and adapted on its expulsion stroke to compress the fuel in said chamber, two independent outlet passageways leading from said chamber, two coaxially arranged reciprocable valve members, one adapted to cooperate with a stationary seat to provide a main by-pass valve controlling one of said passageways, said other member cooperating with a seat on said first mentioned member to provide an auxiliary valve controlling said other pas-

sageway, spring means acting between said members and normally tending to hold said auxiliary valve closed, and means operable at a predetermined point during the expulsion of fuel from said chamber to open said auxiliary valve.

6. In a pump for supplying fuel under pressure to the cylinder of an internal combustion engine, the combination of means providing a chamber for receiving liquid fuel and adapted for communication with said cylinder, a piston reciprocated by said engine and adapted on its expulsion stroke to compress the fuel in said chamber, main and auxiliary outlet passageways leading from said chamber, two coaxially arranged and relatively movable valve members each controlling one of said passageways, means operable during the expulsion of fuel from said chamber to actuate said members whereby to open said auxiliary and main passageways in quick succession, and means operating independently of said actuating means to move one of said members whereby to close said auxiliary passage.

7. In a pump for supplying liquid fuel to the cylinder of an internal combustion engine, the combination with a source of liquid fuel under pressure, a chamber for receiving fuel from said source of supply and adapted for communication with said engine cylinder, a piston driven from said engine and adapted on its expulsion stroke to compress the fuel in said chamber, a second chamber normally drained and maintained at a pressure lower than said fuel supply, a main valve controlling the flow of fuel between said first mentioned chamber and said source of supply, an auxiliary valve controlling the flow of fuel from said first mentioned chamber into said second chamber, and mechanism operable during the expulsion stroke of said piston to close said main valve whereby to cause injection of fuel into said cylinder and then in quick succession to open said auxiliary valve, said main valve and again close said auxiliary valve whereby to terminate the injection of fuel into said cylinder.

8. In a pump for supplying fuel under pressure to the cylinder of an internal combustion engine, the combination of means providing a chamber for receiving liquid fuel and adapted for communication with said cylinder, a piston reciprocated by said engine and adapted on its expulsion stroke to compress the fuel in said chamber, two outlets from said chamber, a main by-pass valve controlling one of said outlets, a pressure relief valve controlling said other outlet, and means operable at a predetermined point during the injection of fuel into said cylinder to open said pressure relief and by-pass valves successively and then close said pressure relief valve.

9. In a pump for supplying liquid fuel to

- the cylinder of an internal combustion engine, the combination with means providing a fuel receiving chamber, a member driven from said engine and operable to compress fuel in said chamber and cause injection thereof into said cylinder, means providing a second chamber normally filled with fuel oil, means providing a constantly drained chamber, and means operable during the expulsion of fuel from said chamber for terminating the injection of fuel into said cylinder including a main by-pass valve adapted when opened to establish communication between said first and second mentioned chambers, an auxiliary by-pass valve adapted when opened to establish communication between said first mentioned chamber and said constantly drained chamber, and mechanism operable to open said auxiliary and main valves successively.
- 10 13. In a pump for supplying fuel to the cylinder of an internal combustion engine, the combination of means providing a chamber for receiving liquid fuel a portion of which is to be injected into said cylinder, a member driven from said engine and movable in said chamber to expel fuel therefrom, main and auxiliary by-pass valves controlling separate outlets leading from said chamber, and mechanism operable during the expulsion of fuel from said chamber to open said main and auxiliary valves successively.
- 15 14. The combination with an internal combustion engine fuel pump having a chamber into which a charge of fuel is drawn and then expelled under pressure to cause a part thereof to be injected into a cylinder of said engine, of means to terminate the injection of fuel into said cylinder by by-passing the remaining part of said charge out of said chamber, said last mentioned means including a valve structure adapted to be actuated by said engine and operable to separate the initial and final portions of the by-pass part of said charge.
- 20 15. The combination with an internal combustion engine fuel pump having a chamber into which a charge of fuel is drawn and then expelled under pressure to cause a part thereof to be injected into a cylinder of said engine, of means to terminate the injection of fuel into said cylinder by by-passing the remaining part of said charge out of said chamber, said last mentioned means including a valve structure adapted to be actuated by said engine and operable to separate the initial and final portions of the by-passed part of said charge, and means operable to prevent the flow of said initial portion back into said chamber during the succeeding operating cycle of said pump.
- 25 16. In testimony whereof, I have hereunto affixed my signature.
